Primary Examiner — Carol P Rademaker(57) **CLAIM**

The ornamental design for a bottle, as shown and described.

DESCRIPTION

FIG. 1 is a top, front, and right side perspective view of a bottle showing my new design;

FIG. 2 is a front elevational view thereof;

FIG. 3 is a right side elevational view thereof;

FIG. 4 is a left side elevational view thereof;

FIG. 5 is a top plan view thereof; and

FIG. 6 is a bottom plan view thereof; and,

FIG. 7 is a bottom, front perspective view thereof.

The broken lines shown in the drawings are included for the purpose of illustrating environmental structure of the bottle and form no part of the claimed design. The shading in the figures is intended to show contour and is not surface ornamentation.
